UNITED STATES PATENT OFFICE.

CHARLES P. SCHLEGEL, OF ROCHESTER, NEW YORK.

DESIGN FOR RIBBON.

No. 37,885.

Specification for Design.

Patented March 6, 1906.

Application filed August 18, 1905. Serial No. 274,797. Term of patent 7 years.

To all whom it may concern:

Be it known that I, CHARLES P. SCHLEGEL, a citizen of the United States, residing at Rochester, in the county of Monroe and State of New York, have invented a new, original, and ornamental Design for Ribbons, of which the accompanying drawing is a representation.

The figure is a plan view of a ribbon, showing my new design.

I claim—

The ornamental design for a ribbon, as herein shown.

CHARLES P. SCHLEGEL.

Witnesses:

F. F. CHURCH,
G. WILLARD RICH.
